UNITED STATES PATENT OFFICE.

MEDERICK HOULE, OF SWAINSBORO, NEW HAMPSHIRE.

MAIL-BAG CATCHER FOR MAIL CARS.

Application filed October 10, 1924. Serial No. 742,837.

To all whom it may concern:

Be it known that MEDERICK HOULE, a citizen of the United States of America, residing at Swainsboro, in the county of 5 Grafton and State of New Hampshire, has invented new and useful Improvements in Mail-Bag Catchers for Mail Cars, of which the following is a specification.

The present invention has for its purpose 10 to provide in a mail bag catcher for mail cars, a construction including a supporting housing provided with supporting arms, the latter being disposed transversely of the door opening and parallel with the side of 15 the car including a jointed releasing device capable of collapsing when engaged with the mail bag, whereby the latter may be clamped against the supporting arms by means of a tensioned arm operatively mounted 20 in said housing.

Another purpose is the provision of a device of this kind including a tensioned arm so disposed in an extended position when set that it will act to swing or throw 25 the mail bag toward and clamp it upon parallel supporting arms which extend transversely of the door opening to permit easy access to the bag by the mail clerk.

It is to be understood that the particulars 30 herein given are in no way limitative and that, while still keeping within the scope of the invention, any desired modifications of detail and desired proportions may be made in the apparatus according to the 35 circumstances.

The invention comprises further features and combinations of parts to be hereinafter set forth, shown in the drawings and claimed.

In the drawings:

40 Figure 1 is a view in perspective of a portion of a mail car showing the catcher applied in accordance with the invention and in the act of engaging a mail bag supported in the usual manner alongside of the track.

45 Figure 2 is a sectional plan view of a portion of the side of the mail car showing the catcher applied and the mail bag caught.

50 Figure 3 is an enlarged sectional view through the supporting housing with the mail catcher set and illustrating the tensioning means for the movable mail bag catching arm.

55 Figure 4 is an enlarged perspective view of the two supporting arms showing an end jaw and illustrating the jointed arm in its extended position.

Referring to the drawings, 1 designates a mail car and 2 a supporting housing secured in position by the holding plates 3, the housing being disposed adjacent one 60 side of the door opening, said housing having a pair of parallel arms 4. The arms project from the interior of the housing parallel with the upper and lower walls of the housing and are disposed transversely 65 of the door opening and in a direction parallel with the side of the car.

The ends 5 of the arms 4 are secured in notches 6 of a plate 7 which acts to hold the 70 arms 4 in parallelism. This plate 7 is provided with a notch 8, the lower edge of which is horizontally disposed when the mail catcher is in operation, that is, in the act of catching a mail bag. The extremity of the lower edge of the notch is rounded 75 off outwardly and downwardly, acting to cam a mail bag catching arm. The upper edge of the notch 8 inclines upwardly and outwardly, also acting as a cam for camming the mail bag catching arm. 80

As previously stated, the housing is supported adjacent one side of the door opening upon the holding plate through the medium of a supporting stud 9 upon which the housing is rockably supported while the 85 plate 7 has a socket 10 for the reception of a stud 11 which projects from the opposite jamb of the door opening in axial alignment with a similar stud 11^a which is pivotally connected with and holding plate 3 and is 90 carried by the door frame. By this construction, the housing and the parallel arms are capable of rotating or rocking substantially a quarter turn to permit the mail bag to 95 be easily removed from the catcher.

Journalized in bearings of the parallel arms 4 and encased in the housing is a drum 12 provided with a groove 13 which receives a chain 14 and projecting radially from the drum is a mail bag catching arm 15. One 100 end of the chain is connected to an eye 16 carried by the base of the arm 15 and the other end of the chain is connected to a tensioned coil spring 17 which, in turn, is connected to one wall of the housing. 105

The arm 15 operates through an elongated slot 18 in the wall of the housing and is long enough to engage the notch 8 when it is in clamping engagement with the mail bag. The extremity of the arm 15 cams against the 110 wall of the notch until it engages with the crotch thereof. The end portion of the

arm 15 has an abutment lug 19 which contacts with one of the arms 4 when the mail bag catching arm is released. The abutment arm 19 contacts with one of the arms 4 about the same time that the arm engages with the crotch of the notch.

- A mail bag tripping device consisting of a toggle arm 20 is pivoted as at 21, between the end portions of the parallel arms 4. This 10 mail bag tripping device comprises the two toggle sections 22 and 23 pivotally hinged or jointed as at 24, by means of a pin. The section 23 operates in a bifurcation 25 of the end of the section 22. The end of the section 15 23 is rounded off, as at 26, to permit the section 23 to collapse when a mail bag engages with the setting device. The section 23 has an abutment end 27 which abuts with the crotch of the bifurcation, as at 28.
- 20 The construction and arrangement of the pivot of the section 23 with relation to the crotch of the bifurcation are such as to retain the section 23 extended at a slight angle to the section 22 when the tripping device is 25 disposed to hold the mail bag catching arm in an operative position. The extremity of the section 23 has a rounded end 29 engaging a similarly formed notch 30 in the arm 15 for holding the arm 15 set in an operative 30 position for catching the mail bag.

In operation, the device is held by the mail clerk or operator in the extended position shown in Figure 1 and when the mail bag contacts with the collapsible tripping device, 35 the two sections 22 and 23 collapse in a direction toward the parallel arms 4 while the arm 15 is operated through the tension of the spring for catching and clamping the mail bag against the arms 4, in which case 40 the tripping device will swing to a position between the parallel arms. The housing may then be rocked in any suitable manner so as to dispose the protruding end of the housing within the car as well as disposing 45 the two arms 4 in positions whereby the mail bag may be easily removed. In fact, when the tripping device collapses inwardly toward the car, it being pivoted at 21, will cause the whole mechanism to swing inwardly, and the trip may then be grasped 50 and used for rocking the mechanism, al-

though it is possible to do this by any other suitable means or by simply grasping the housing for imparting thereto a partial rotatory movement.

55

The invention having been set forth, what is claimed is:

1. A mail bag setting device comprising a pair of parallel arms provided at opposite ends with means for pivotally mounting them on the opposite sides of a mail car door frame, a housing carried at one end of said arms, a mail bag catcher arm having a pivotal mounting in said housing and provided with means for yieldingly impelling it toward said parallel arms, and a toggle joint tripping arm having one of its elements pivotally mounted at its extremity at the ends of the parallel arms remote from the housing and the other element having a terminal 70 engaging a seat in the catcher arm, said elements having abutting ends normally holding the elements in approximate alignment, and the parallel arms normally holding the tripping arm in a position for impact with a mail sack at or adjacent the point of connection between its elements.

2. A mail bag setting device comprising a pair of parallel arms provided at opposite ends with means for pivotally mounting them on the opposite sides of a mail car door frame, a housing carried at one end of said arms, a drum enclosed within the housing and pivotally mounted between said arms, a mail bag catcher arm projecting radially from said drum and extending through a slot in the housing, a flexible member traversing the drum and connected at one end to said arm, a spring connecting the other end of said flexible member with a point in the housing, and a toggle joint tripper arm having one of its elements pivotally mounted between the parallel arms at the end remote from the housing and the other element provided with a terminal for engagement with a seat in the catcher arm when the latter is disposed at an angle in divergence with the parallel arms.
